THERAPEUTIC DEVICE

Bassett R. Robertson, San Diego, Calif., assignor
to Freez-A-Bag, Inc., Los Angeles, Calif., a
corporation of California

Application November 26, 1938, Serial No. 242,503

1 Claim. (Cl. 62—1)

This invention relates to improvements in therapeutic devices, specifically flexible containers filled with or containing a solution which is normally liquid but which is capable of being frozen or having its temperature reduced to below the freezing point of water and still maintain a flexible or moldable condition. The invention further relates to a therapeutic device in the form of a pliable or flexible container filled with a loose or mobile granular substance having a temperature below the freezing point of water and preferably below 28° F., the container and its contents being flexible and pliable so as to permit the container to be molded by hand to cause it to conform to bodily contours.

The invention furthermore pertains to a form of apparatus and a method of facilitating the use of such therapeutic devices.

Cold packs are a necessity in the treatment of many cases of infection, post operative conditions, etc. Cold packs are, for example, used very extensively to prevent bacterial development in certain cases of infection and to prevent hemorrhages as a result of tonsillotomy and the like. Heretofore, rubber bags containing chipped ice have been employed but obviously the heat-absorbing capacity of the usual cold bag is limited. Ice has a melting point of 32° F. and it is impossible to reduce the temperature of a desired section of the body as readily with ice as by the application of another substance having, for example, a temperature of 22-24° F. In order to produce a given heat-absorbing capacity with ice, a much larger volume and weight of ice is necessary than is the case with a substance having a temperature of 22° F., for example. By reason of the bulky character of usual ice bags, patients are subjected to considerable discomfort since many regions to which an ice pack need be applied are incapable of sustaining any appreciable weight. A still further disadvantage to the use of ice lies in the fact that ice crystals and the edges of broken ice are sharp and angular and exhibit a tendency to puncture the bag. These angularities and sharp edges also cause discomfort to the patient.

The present invention obviates all of the disadvantages hereinabove referred to and provides a flexible container which for a given heat-absorbing capacity weighs only a fraction as much as an ice bag of the same heat-absorbing capacity. Moreover, therapeutic devices of this invention are flexible, pliable and adapted to conform to the body so as to obtain better contact. In addition, the cold bags of this invention need not

be refilled and are free from the jagged edges, protuberances, etc., which characterize ordinary ice bags.

It has been discovered that aqueous solutions containing glycerine may be sealed within a thin flexible container and the contents of such container then reduced to a very low temperature before such aqueous glycerine solution solidifies. Furthermore, it has been found that such apparently solid glycerine solutions may be molded and are flexible even though they are subjected to but slight pressure of the hand, thereby permitting the container and its contents to be applied to any curved surface or portion of the body and obtain practically perfect contact between the container and the surface.

The container in its preferred form is a relatively thin container provided with a substantially smooth external surface. Means have been devised whereby these containers may be sealed to enclose a suitable quantity of the aqueous glycerine solution and means have also been provided whereby the containers may be rapidly and efficiently chilled or frozen, the freezing cabinet permitting rapid absorption of heat from the containers so that a relatively small number of such containers may supply the needs of a great many patients.

It is an object of the invention, therefore, to provide a therapeutic device in the form of a heat-absorbing pad, bag, or other container, the container and its contents being flexible, bendable and moldable even though its contents are at temperatures below the freezing point of water.

A further object of the invention is to provide a substantially smooth-surfaced, flexible, sealed container, the contents being capable of assuming a granular or sand-like condition at temperatures below the freezing point of water.

A still further object of the invention is to provide means and methods of preparing and utilizing therapeutic devices capable of absorbing large amounts of heat in an effective manner.

These and other objects, advantages, uses and modifications of the invention will become apparent to those skilled in the art from the following detailed description of preferred forms. In order to facilitate understanding, reference will be had to the appended drawing, in which:

Fig. 1 is a perspective view of a simple therapeutic device made in accordance with this invention, a portion of this device being broken away.

Fig. 2 shows another form of device in use and illustrates its flexibility.

Fig. 3 is a side elevation, partly in section, of a refrigerating cabinet in which the therapeutic devices of this invention may be conditioned.

As shown in Fig. 1, the container may comprise a hollow, substantially seamless pad 10 made of rubber, rubber composition, or other flexible, relatively limp, preferably semi-elastic material. In one form of the device a tubular extension may be formed, such tubular extension being integral with the walls of the device, such tubular extension being used for filling the container 10 with a suitable solution or liquid medium which is liquid at atmospheric temperatures but which is capable of solidifying or being frozen to temperatures below the freezing point of water without the formation of a rigid or strong solid mass. After the container has been filled with such a liquid, the tubular extension may be forced into the container to assume the position indicated at 11 and the opening then sealed with a plug or cemented. As a result, the container 10 is substantially smooth and is free from those removable closures which characterize the ordinary ice bag.

The liquid or solution used in filling the container should have the property of being chilled to temperatures appreciably below the melting point of ice without the formation of hard, strong, inflexible bodies. Solutions of glycerine and water have been found to be eminently suited for this purpose. Ordinarily, such solutions may contain from about 12% to 25% of glycerine by volume, the remainder consisting of water or water with but a minor proportion of some other substance.

When a solution is employed, said solution being made by mixing 1 volume of glycerine with 5 volumes of water, it will be found that the solution will solidify or freeze at about 23.5° F. and such solution containing approximately 17% of glycerine, appears to be admirably suited for the uses contemplated, particularly in hospitals, sanitaria, etc.

Containers filled with solutions of the character stated may be chilled or frozen in a number of different ways. The typical 5 to 1 solution mentioned is readily converted into the desired state by placing the containers or bags filled with the solution upon trays or shelves of a refrigerator provided with coils capable of expanding a refrigerant, the temperature in such refrigerator or on the surface of the shelves being preferably below about 20° F. In order to facilitate the freezing operation, it is desirable that the therapeutic devices of this invention be placed in virtual contact with the expansion coils.

A form of device which has been found to be eminently suited for the preparation and conditioning of the therapeutic devices of this invention is illustrated in Fig. 3. As there shown, the device comprises an exterior housing 15 provided with a freezing compartment, generally indicated at 16, and a suitable door 17. A conduit 19 may extend upwardly from the liquid refrigerant storage 18 and then zig-zag in a substantially horizontal plane so as to form a shelf 20. Additional expansion coils arranged in horizontal spaced planes, such as the shelves 21, 22, etc., are connected to the end of the shelf 20 by suitable connecting conduits. The line 23 from the lowermost shelf is connected to the compressor and other elements of the refrigerating system which, in the exemplary showing of the figure, are located in the bottom of the housing. The various shelves 20, 21, 22, etc., may

also include thin covering sheets 20', 21', etc., suitably fastened to the upper surfaces of the coils so as to afford a smooth surface on which the therapeutic devices may be supported.

5 Front edge portions of the sheets 20', 21', etc., may be turned down or under as indicated at 27 and 28 so as to form edges shielding the ends of the thin sheets 20', 21', etc., may be bent upwardly and fastened to the rear wall of the cabinet as indicated at 28', for example.

The spacing between the shelves, such as the shelves 21 and 22, should be sufficient to permit the ready introduction of the therapeutic devices 15 while at the same time permitting the heat-absorbing effect of the coil constituting shelf 21 to exert a refrigerating effect upon any therapeutic device placed upon the lower shelf 22. If, for example, the therapeutic devices are between 0.5 and 0.75 inch in thickness, the space between the top of the lower shelf and the bottom of the upper shelf may be only about 3 inches. By expanding a gasified refrigerant in the coils arranged as shown and by supporting the therapeutic devices 25 upon the metal covering sheets which in turn are welded, soldered or otherwise directly connected to the coils, the contents of the therapeutic devices may be rapidly chilled to below their solidification point.

30 If, for example, a 5 to 1 solution is contained in the therapeutic devices 10, the coils and shelves of the conditioning cabinet may be maintained at about 15° F. The 5 to 1 solution of the therapeutic devices will solidify as stated at about 23.5° F.

35 In the event a patient requires a cold pack, the attendant or nurse may remove the therapeutic device from the refrigerating cabinet and it will be found that even though such device appears fairly rigid, it can be molded, bent, flexed and distorted by simple pressure of the fingers, the contents appearing to be granular or crystalline and substantially free from large lumps or pieces with jagged edges. Instead, the grainy material within the bag appears to be small and rounded and 40 as a result the therapeutic device may be applied to the desired portion of the patient's anatomy and molded so as to insure thorough contact.

Fig. 2 illustrates a long, narrow bag or container which may be adapted to lay flat when in 50 extended form, but after the contents have been reduced in temperature to the required extent, such bag can be molded by finger pressure to fit around the neck of the patient, the ends of the bag being then connected or removably connected. 55 Bags of this type are preferably provided with elastic coverings.

By varying the proportion of glycerine contained in the solution, within the range heretofore given, the heat-absorbing capacity of the 60 solution and of the therapeutic device in which it is contained may be varied, without destroying the peculiar characteristics attained by freezing said solutions. If less than about 8% or 10% of glycerine is contained in the solution, the peculiar 65 grainy character of the frozen product is not attained. The contents of therapeutic devices composed of a solution made by mixing 6 parts of water with 1 of glycerine will be found to have a freezing point of about 24.9° F., while the freezing 70 point of a solution made by mixing 1 part of glycerine with 4 parts of water will be found to be about 20° F.

In all events, it is desirable that the contents be capable of attaining temperatures below about 75 29° F. In making these solutions it has been

found that technical grades of glycerine are entirely satisfactory. Glycol derivatives and substitution products such as diethylene glycol, etc., can be used instead of or in addition to glycerine with similar results.

After the heat-absorbing capacity of a therapeutic device of this invention has been utilized and the contents have liquefied and have absorbed sufficient heat so that a desired chilling effect is not being attained, the container is returned to the refrigerating or conditioning cabinet to be again frozen. It is to be noted that in this manner the attendants and nurses need not fill and refill the bags as is the case when ice is employed, thereby greatly facilitating their work and effecting a large saving in time. The usual type of refillable bag has but a limited life due to the action of sharp and hard ice particles on the bag and due to the repeated strains imposed thereon by twisting the normal screw-threaded closure, but the devices of this invention are free from these objections and can be used for extremely long periods of time.

Moreover, attention is again called to the fact

that the therapeutic devices of this invention are provided with substantially smooth external surfaces and the heat-conducting capacity of the surface of the container is virtually uniform. For this reason the patient is not subjected to the angularities of closure members nor the more intense heat-absorbing effect of a large metal cap or opening as compared with the fabric covering ordinarily found on the usual style of ice bag.

10 I claim:

A device for cooling a portion of the body of a patient, said device comprising a bag constructed of thin flexible rubber and having sealed therein a quantity of water and a sufficient quantity of 15 depressant of the freezing point of the water and having the property of forming therewith, at temperatures a few degrees below 32° F., a slushy mass that may be molded by the fingers of an operator, without substantial risk of puncturing the walls of the bag, to conform to the shape of 20 such body portion of the patient, said depressant being selected from a group consisting of glycerine, glycol and diethylene glycol.
